BAG TURNING AND CLEANING MACHINE

Application filed November 6, 1925. Serial No. 67,805.

Generically this invention relates to bag-cleaning machines, but it more especially comprehends the type adaptable to automatically turn and clean bags having extraneous material adhering to the inside, and to clean without turning those having such material adhering to the outside.

A primary object of this invention is to eliminate all chains and other conveying means around which strings and the fraying edges of bags might hang, and to convey the bags principally by air blast and gravitation; to take the bags from a low position where they can be placed with ease of handling and whence they can be easily fed to the machine; to draw them by air blast in an upward direction into a cleaning chamber, and to discharge them therefrom in an elevated position, whence they descend by gravity over other cleaning means.

An important object of this invention is the provision of a mouthpiece holding means automatically adjustable to the mouths of different sized bags for initially holding the bag to effect its delivery to the machine either turned or unturned depending upon the manner of feed to the said holding means, and releasable to permit travel of the bag through the machine.

Another object of this invention is the provision of an air blast means for shaking and flapping the free end of the bag as it is initially held by the mouth piece or holding means, and additional means for holding the forward end of the bag to permit similar air blast treatment of the other end after its release by the initial holding means, and releasable to permit travel of the bag through the remaining cleaning mechanism.

Another object of this invention is the provision of means for simultaneously brushing one side of the bag, rapidly vibrating the bag fabric, and drawing air through the bag fabric toward the side being brushed; for then brushing the opposite side of the bag, vibrating the bag fabric and drawing air through it in a similar manner; and for conveying the bags over the brushing, vibrating, and suction means in an approxi-

mately continuous stream to insure a maximum of cleaning to each bag.

Still another object of this invention is the provision of a machine for cleaning bags, designed to subject each bag to a plurality of cleaning operations as it is conveyed therethrough, the cleaning mechanism including an air blast chamber and a plurality of cleaning or brushing units associated with suction means, such means being yieldable so as to prevent damage to the machine or to the bags should solid substances be present during the cleaning operation.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a diagrammatic view of the machine partly in elevation and partly in section.

Fig. 2 is a side elevation of the machine itself.

Fig. 3 is a top plan view of the same; as on line 3—3—3 of Fig. 1.

Fig. 4 is a central vertical section taken on the line 4—4 of Fig. 3 showing the position of the turned bag;

Fig. 5 is a similar view to Fig. 4 and showing the position of an unturned bag and one of the contact fingers in operative position;

Fig. 6 is a side detail elevation of the bell crank levers and a portion of the frame, with parts broken away to show the sides and brakes in the interior;

Fig. 7 is a front elevation of the mouthpiece in collapsed position, and showing in outline the manner of putting a bag over the mouthpiece when it is desired to turn the bag;

Fig. 8 is a similar view to Fig. 7, showing the mouthpiece in expanded position holding the bag.

Fig. 9 is a similar view to Figs. 7 and 8, showing in outline the manner of putting a bag over the mouth piece when it is desired to clean the bag without turning.

Fig. 10 is a side elevation of the valve mechanism.

Fig. 11 is a vertical section of the brushes and speed control rings.

5 In the illustrated embodiment characterizing this invention there is shown the main supporting frames 1 and 2 provided with suitable bearings in which are mounted a plurality of longitudinal shafts including a main 10 driving shaft 3, and principal auxiliary shafts 4, 5, 6, 7 and 8, interconnected by gearing comprising gear wheel 9 suitably locked on main drive shaft 3 and adapted to mesh with gear 10 mounted on shaft 5. Also 15 mounted on shaft 5 adjacent thereto is pinion 11 adapted to mesh with gear wheel 12 suitably locked on shaft 4 and large gear wheel 13 mounted and securely locked to shaft 6 which is adapted to mesh with gear wheel 14 20 mounted on and secured to shaft 7 which meshes with gear wheel 15 carried by and secured to shaft 8.

The frame 2 formed with an inwardly extending section 16 which with cover section 17 25 forms valve chamber 18, and secured to section 17 is a centrally disposed dome like section 19, forming a cover for cleaning chamber 20. Section 2 joins section 19 forming a continuation thereof forwardly and downwardly to form a seat for mouth pieces 24 and 25. Mouth pieces 24 and 25 are adapted to slide transversely in upper and lower ways or grooves. Arms 35 are fulcrumed to extensions 36 of cover 17 as at 37. Between the 30 fulcrums 37 and their rear ends, the arms 35 are provided with rollers 40 adapted to travel on the cylindrical or barrel cams 41. Cams 41 are carried by and suitably secured to shaft 8. Cords 135 are attached to springs 136 35 which are attached to the rear ends of arms 35. Cords 135 run over sheave wheels 137 and carry at their lower ends weights 138. The forward ends of arms 35 are connected to mouth pieces 24 and 25 by tension rods 139 40 and compression springs 140. Hence as shaft 8 and cams 41 revolve, they move mouth pieces 24 and 25 inwardly toward the center of the machine, and the weights 138 move the said mouth pieces outward giving the mouth 45 pieces a transverse sliding reciprocating motion. The weights 138 and springs 136 tend to pull the mouth pieces apart until they tighten within the mouth of the bag B as shown in Fig. 8. It is obvious that as the 50 lateral movement of said mouth pieces is governed by the size of the mouth of the bag, the same is automatically adaptable in connection with bags of various widths. Also, when the tension of the bag stops the outward 55 movement of the mouth pieces 24 and 25, the weights 138 do not stop instantly, but stretch the springs 136 and thereby come to a stop gradually. They thus exert an outward pull 60 on the mouth pieces due to their momentum, 65 in addition to the pull due to their weight,

and as this occurs at the time of the valve opening, they give a maximum holding effect on the bag at the time when it is most needed.

Leading rearwardly from the valve chamber 18 is a pipe or air conduit 42 to a suction fan 141. The suction of said fan with respect to said cleaning chamber 20 is governed by valve 43 positioned in said valve chamber 18 mounted on valve shaft 44. Mounted on shaft 7 adjacent to gear wheel 14 is a cam 45 over which is adapted to travel roller 46 rotatably mounted as at 47 in guide arm 48 pivoted on shaft 8 and which is adapted to actuate valve 43 through the instrumentality of link 49 connected to lever 50 keyed to valve shaft 44. As cam 45 releases the roller 46 coil spring 51 attached to frame 2 and to the upper end of bell crank or lever 50 pulls the valve suddenly open similar to the action of a steel trap, which exhausts the air from the cleaning chamber 20, the outside air striking bag B placed over the mouth pieces 24 and 25 as shown in Figs. 4 and 7 with sudden force or impact drives it into the machine, which action turns the inner side out. 90 As the valve 43 closes it comes to its seat before roller 46 and guide arm 48 have come to the end of their travel, and during the last portion of which travel they compress the spring 52 attached to link 49 as at 53 and to pin 54, as slot 55 moves thereover. The transverse direction of valve chamber 18 is greater than that of cleaning chamber 20 as clearly shown in Fig. 3, and the valve 43 is round on its forward edge as at 56 so that lint or other fibrous material loosened by the air current from the bags will not lodge thereon but be carried on out of the machine. The valve tapers to a point at its opposite edge to allow free passage of the air.

105 Mounted in suitable bearings in section 16 of the frame 2 is shaft 57 to which are rigidly keyed the swinging arms 58 between which is adapted to be mounted nip roller 59 secured to shaft 60 mounted in suitable bearings in the free ends of said arms so as to permit nip roller 59 to yieldingly contact with main drum 61 securely mounted on shaft 6 to normally form a seal for the upper end of cleaning chamber 20, said roll extending the full width of the cleaning chamber. Shaft 60 and nip roll 59 are positively driven from shaft 8. The under side of shaft 57 is concaved as at 62 to permit free rotation of roll 59, and the concaved face 63 in frame section 16 permits a partial rotation of shaft 57 to allow nip roll 59 to swing away from drum 61 to permit the passage thereunder of a bag B in a wad or when containing some hard substance without injury to the bag or to the machine.

110 The drum 61 is formed with a plurality of circumferentially spaced grooves in which are adapted to be seated feed rings 64 rough on their outer surfaces. A corresponding plurality of fingers 65 are secured to shaft 66 115 120 125 130

- mounted in suitable bearings in cover A and cap plate 30 and are adapted to be alternately raised and lowered in cleaning chamber 20 through the instrumentality of guide arm 67 5 pivotally mounted on shaft 7, and roller 68 mounted on pin 69 in the free end of arm 67 for contact with cam 70 rigidly mounted on shaft 8, and link 71 also pivoted on pin 69 and at 72 to lever 73 keyed or otherwise secured to shaft 66. The raised and lowered positions of the fingers 65 are clearly shown in Figs. 4 and 5, respectively, and when lowered each of said fingers is adapted to rest centrally above and nearly touching feed 10 rings 64 as shown in Figs. 3 and 5 of the drawings, also illustrating how the bag B is held against the rough surfaces of feed rings 64 of revolving drum 61 and fed to nip roll 59, the polished under faces of said fingers 65 15 offering practically no resistance.
- Pivottally mounted on the shaft 7 are the depending arms 74 in the lower ends of which are adapted to be mounted the shaft 75 on which are spaced and rigidly mounted a plurality of roughened or toothed speed control rings 76, one of which is shown in Fig. 6, the said shaft 75 being driven by chain and sprocket from shaft 7 as diagrammatically shown in Fig. 1. Extending at right angles 20 from said arms 74 pivotally secured thereto as at 77 are rods 78 extending through frame 1 and secured by nuts 79 for the purpose of maintaining the normal position of arms 74 as shown in Fig. 6 but yieldable by compression 25 springs 80 mounted on rods 78, the tension of said springs being governed by adjusting nuts 81. The speed control rings 76 rotate relatively slowly in a direction opposite to the pitch of the teeth 82 for a purpose hereinafter more fully apparent. Positioned 30 below said drum 61 and facing speed control rings 76 is a casing 83, the upper front section extending to the left from a point 84 to a point 85, thence upwardly curved around 35 the edge of speed control ring 76 to a point adjacent to drum 61 forming guide or slide plate 86 so as to strip the bag from the drum 61 and deliver it to the speed control ring 76 as will hereinafter more fully appear.
- The lower front section of said casing 83 40 is similarly constructed extending upwardly from a point 87 to 88 and thence downwardly to 89 to form slide plate 90. The casing 83 is provided with a longitudinal opening 45 91 and secured across said opening is a suitable screen as indicated at 92. See Fig. 11. Housed within the casing 83 and securely mounted on shaft 93 extending through the said casing and supported in suitable bearings in frame 1, is a brush 94 of open or squirrel cage design, the tufts of the brush being adapted to extend within the opening 91 to contact with the material passing thereover, the said shaft 93 preferably belt driven by 50 pulley 93' secured thereon and from a coun-
- ter shaft above the machine and source of power not shown. Leading out of the casing 83 to a suction fan (not shown) is a pipe or air conduit opening 95, so that as the bag slowly travels over the opening 91 such extraneous material adhering thereto as may be dislodged by the rapidly revolving brush 94 will be drawn through the brush and from the casing through pipe opening 95.
- Positioned just below the casing 83 is a second set of speed control rings similar to those above described, except being relatively reversed so as to contact with opposite sides of the bag with respect to the speed control rings 76 and brush 94, respectively.
- Pivottally mounted on shaft 6 are the depending arms 96 in the lower ends of which are mounted shaft 97 which is driven by chain 97^a and sprockets 97^b from shaft 6 as diagrammatically shown in Fig. 6, and carries securely mounted thereon a plurality of spaced speed control rings 98, similar to speed control rings 76 heretofore described, except that they rotate at a lower speed than speed control rings 76. Extending at right angles from said arms 96 pivotally secured thereto as at 99 are rods 100 extending through and yieldably secured to frame 1 by adjusting nut 101, nuts 102, and compression spring 103, the latter seating against frame 1 and nuts 102, to permit yieldable movement of arms 96 commensurate with the thickness of material passing between rings 98 and slide 107, which is similar to the operation of the arms 74.
- Facing the toothed speed control rings 98 and in substantially the same horizontal plane is a casing 104 similar to casing 83, having an upper front section secured as at 105 curved downwardly to a point 106 in the same horizontal plane as shaft 97 and then curved slightly to accommodate the toothed speed control rings 98 and upwardly forming the guide or slide plate 107. The lower front section is substantially similar except being secured as at 108 and is curved upwardly to 109 and downwardly forming a guide or slide apron 110. Between the points 106 and 109 an opening 111 is formed in casing 104 over which is suitably secured a screen as indicated at 112, said screened opening adapted to permit contact of the brush with the bag as it passes thereover, corresponding to 92 and for a similar purpose.
- Housed in casing 104 is a brush 113 similar to brush 94, mounted on shaft 114 extending through said casing and suitably supported on frame 1, being preferably belt driven by pulley 114' mounted thereon and from a countershaft above the machine, similar to shaft 93, the tufts of said brush 113 projecting slightly beyond opening 111 to contact with the bag or material being cleaned as it travels thereover, as explained in connection with brush 94. The main body

of the casing 104 is identical to casing 83 including an air conduit opening 142 leading therefrom to a suction fan, which for brevity of description is not shown.

5 A plurality of arms 115 are fulcrumed on shaft 116 mounted in suitable bearings in frame 1, one of said arms forming a bell crank lever as shown in Figs. 2 and 6. Rigidly mounted as at 117' in the upper ends of 10 said arms 115 is brake 117, and a spring (not shown) carries said arms forward causing brake 117 to contact with drum 61. Just above casing 104 is a cam shaft 118 mounted in suitable bearings in frame 1, suitably 15 driven by chain and sprocket from shaft 7 which being well known construction, for brevity of description is not shown, and on which is securely mounted cams 119, 120 and 121. Cam 119 is adapted to contact with 20 lower arm of bell crank lever 115, moving brake 117 away from drum 61. Similarly brake 122 is mounted in the upper ends of arms 123, one of which extends beyond the fulcrum 124 to form an actuating lever. 25 Brake 122 is adapted to contact with slide 86 by means of a suitable spring (not shown), said brake being moved away from slide 86 by cam 120 traveling over lower arm of lever 123. Likewise brake 125 is mounted on the 30 upper ends of arms 126, which are fulcrumed at 127 and one of which arms forms a bell crank lever. Brake 125 is adapted to contact with slide 90 by means of a spring (not shown) and is moved from contact with said 35 slide by means of cam 121 engaging the free arm of bell crank 126, as will be more fully hereinafter explained.

Resting on the outer edge of cap plate 30 is a rotatable spool 131, and pivotally connected 40 to said cap plate 30 by link 133, for the purpose of initially holding the bag by lightly gripping one edge and maintaining the same in position to be engaged by primary holding means 24 and 25, which becoming effective automatically pull the bag from beneath the spool 131.

Operation

While it is thought the operation of the 50 machine is clear from the above description, nevertheless, it might be well to explain certain details more fully, having in mind that the various associated mechanisms from the mouthpieces 24 and 25 to brush 113 are coordinated to operate in automatic synchronization for effecting the automatic cleaning of each bag and either turning or not turning the bag to be cleaned, dependent upon whether it is initially fed over both upper 55 and lower lips of the mouth pieces 24 and 25 as shown in Figs. 4, 7 and 8, or over the upper lip only as shown in Figs. 5 and 9, respectively, in either case feeding the upper edge of the bag initially under spool 131.

65 Assuming the first bag to be cleaned to be

an unturned bag with meal or similar material adhering to the inside of the bag, the operator holds it as shown in Fig. 7, putting it over the upper and lower lips of mouthpieces 24 and 25 and feeding the upper edge between spool 131 and the stationary piece 30 of the frame, the weight of the spool being sufficient to hold the bag until the mouthpieces expand, which action automatically disengages and stretches it tightly over the 70 said mouthpiece as shown in Fig. 8. Valve 43 then automatically opens suddenly permitting the suction fan to draw air from the cleaning chamber above the drum, and, with the atmospheric pressure, driving the bag into the machine and at the same time turning it inside out, flapping it, and drawing air through the meshes of the bag fabric, and carrying away such extraneous matter as is removed. The air flowing thus into the mouth 75 of the bag and out through the meshes of the bag fabric inflates or balloons the bag. Then the fingers 65 lower almost to the drum and stop there. The said fingers coming down on the ballooned bag press it flat, and simultaneously the air pressure within the bag spreads it laterally and takes out the folds and wrinkles. The valve starts closing while the fingers are lowering, and closes tightly against its seat after the fingers are near the 80 drum, this allowing the air pressure within the bag to spread it flat between the fingers and the drum as just described. Then with the fingers stationary near the drum and the bag between them, the mouthpieces 24 and 25 85 collapse to the position shown in Fig. 9. The fingers 65 then move on down against the drum 61, and press the bag against the rough feed rings 64, causing it to be advanced under the nip roll 59, at which time brake 117 90 is in its retracted position away from drum 61, allowing the bag to fall as shown in Fig. 6.

Supposing the second bag to be similar to the first except longer, being carried into the machine as in the previous instance, the speed of the drum 61 being such that when the second bag is blown into the cleaning chamber the first bag is not fed entirely out of 95 said chamber but its rear or open end has reached the point of 61', and as the air blast vibrates and flaps the forward end of the second bag it simultaneously sweeps the rear end of the first bag forward, vibrating and flapping it against roll 59, and at the same time the first bag is feeding out of the cleaning chamber so that when the fingers 65 100 press the second bag against feed rings 64 and it starts to feed there is an appreciable distance, as for instance, seven inches, between the rear end of the first and the forward end of the second bag.

Suppose the third bag is a turned bag with 105 extraneous material adhering to the outside thereof—the operator follows the same pro-

cedure identically as in the two previous instances except feeding this bag over the upper lip only of the mouthpiece as shown in Figs. 5 and 9, it hanging down past the lower lip as will be obvious, and as valve 43 opens the bag is drawn into the machine but without turning it as shown in Fig. 5, it then being acted on similar to the bags above described. This bag, if it is a short one, leaves a much greater distance between it and the preceding bag than if both were of maximum length, the fingers, however, press the drum over a sufficient arc to feed forward a long or short bag.

As the bag comes from the nip roll 59, Fig. 6, brake 117 is back or retracted and the forward end of bag falls of its own weight on slide 86, and by the time it reaches said slide, brake 122 is also back and allows it to fall down to the speed control rings 76 which grip the bag. The distance is such that they grip the shortest bag before its rear end has passed from under the nip roll 59. Then as the speed control rings 76 revolve clockwise the bag falls on down against the rapidly revolving brush 94. Brake 117 then moves forward against the bag pressing it lightly against the drum 61. Brake 122 then moves forward against the bag pressing it lightly against slide 86, holding one bag while brake 117 has moved back to admit the following bag, as clearly shown in Fig. 6. The weight of the bag, the forward brushing of brush 94, and the friction of the revolving drum 61, tend to pull the bag down. The friction of the brakes tend to hold it back. The speed control rings 76 control its speed, molding it to its proper velocity and permitting the brush to rapidly brush its surface. As the forward end of the bag comes to slide 90, brake 125 is back allowing the bag to fall down to slowly revolving speed control rings 98 and thence down past rapidly revolving brush 113. Brake 125 then moves forward pressing the bag lightly against slide 90, and speed control rings 98 hold the bag to its proper downward velocity and permit the brush 113 to brush it in similar manner to those above described. The teeth on the feed control rings 76 and 98 are in the direction to release the bag and the air suction tends to pull the bag from them.

As the bag passes the speed control rings, the suction within the casing pulls it to a concave form between the tufts of the brush as it passes over the opening in the casing as shown in Fig. 11 at 92 and as the brush revolves the tuft throws the bag to a convex form, as shown in Fig. 11 at 111, and as the same is revolving rapidly the moving from concave to convex form gives the bag a very rapid trembling vibratory action, and all extraneous matter thus loosened is carried off by air suction.

The speed control rings 76 carry the bag forward more slowly than does the drum 61

which causes the bag following to gain on the one preceding, so that while bags of maximum length are, say, seven inches apart on drum 61, they are only, say, four inches apart as they pass brush 94, and as speed control rings 98 run more slowly than speed control rings 76, again each bag gains on the bag ahead of it so that as bags of maximum length pass over brush 113 they are only, say, two and one half inches apart, in which case each brush is brushing an almost continuous line of bags, and bags are being discharged in a practically continuous stream. Passing from the lower brush the bag falls onto a conveyor belt 129 which conveys it from the machine.

In practice, I have found that the form of my invention illustrated in the accompanying drawings and referred to in the above description as the preferred embodiment, is the most efficient and practical; yet, realizing the conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I claim is:

1. In a bag cleaning machine, the combination of a chamber, suction means, a connection from said suction means to said chamber, a valve in said connection, means adapted to open and close the said valve at regular time intervals whereby the suction means draws the bags into the said chamber at such regular time intervals, means adapted to discharge the bags from the said chamber, a revolving brush adapted to brush the bag as it is so discharged, and means adapted to move a bag of maximum length over the brush in approximately the said time interval.

2. In a bag cleaning machine, the combination of a chamber, suction means, a connection from said suction means to said chamber, a valve in said connection, means adapted to open and close the said valve at regular time intervals whereby the suction means draws the bags into the chamber at such regular time intervals, means adapted to discharge the bags from the chamber, a series of cleaning units, each unit comprising a rotatable brush and suction means in communication therewith, whereby a current of air is drawn through the bag and brush, each of said units adapted to brush opposite sides of the bag consecutively as it is so discharged, and means adapted to move a bag of maximum length over each brush in approximately the said time interval.

3. In a bag cleaning machine, the combination of a chamber, suction means, a connection from said suction means to said chamber,

a valve in the said connection, expansible releasable means adapted to hold the mouth of the bag as the suction means draws the bottom of the bag into the said chamber and flaps the bottom of the said bag, a rotatable conveyor in connection with said chamber, means for releasing bags from the holder, a yielding means associated with said chamber and said conveyor, means for pressing said bags into contact with the conveyor immediately following its release from the holder to deliver the bottom of said bag to the yielding means, said yielding means adapted to hold the bottom of the said bag as the said suction means pulls and flaps the mouth of the bag, and the said yielding means adapted to discharge the bag from the said chamber.

4. In a bag cleaning machine including a cleaning chamber, means for delivering the bags to said chamber, conveyor means for conveying the bags through the machine, a plurality of cleaning units located in the path of travel of the bags, each unit comprising a brush and suction means, a rotatable toothed means located on the opposite side of said path from its respective unit for feeding the bags thereto, each unit adapted to simultaneously brush and draw air through each bag as it passes thereover, and means for delivering the bags from the machine.

5. In a bag cleaning machine including a cleaning chamber and means for delivering the bags thereto, means for conveying the bags through the machine, a plurality of cleaning units located on alternate opposite sides of the path of the bags, a rotatable toothed member for feeding the bags to each unit located on the opposite side of the path of the bags from its respective unit, each unit adapted to simultaneously brush and draw air through each bag as it passes thereover, and means for conveying the bags from the machine.

6. In a bag cleaning machine comprising a holder for releasably engaging the mouth of a bag, a suction means, a cleaning chamber between and connected with the holder and said suction means whereby an air current is drawn through said holder and said chamber to turn the bag simultaneously with its being drawn into said chamber, a conveyor extending into said chamber, means for shutting off the air current, means for releasing the bag from the holder, means for pressing said bag into contact with the conveyor immediately following its release from the holder, means for receiving the bags from said conveyor and for conveying the bag to the delivery point of the machine, and a series of cleaning means for operating on the bag during its travel through said machine.

7. In a bag cleaning machine comprising a holder for releasably engaging the mouth of a bag, a suction means, a cleaning chamber between and connected with the holder and

said suction means whereby an air current is drawn through said holder and said chamber to turn the bag simultaneously with its being drawn into said chamber, means for shutting off the air current, means for effecting disengagement of the bag from the holder, conveyor means extending into said chamber, means normally elevated within the chamber but movable to lowered position to contact the bags with said conveyor means to effect their conduct through said chamber, additional means for advancing the bags to the exit of the machine, and means for subjecting each bag to a series of cleaning operations during its travel through said machine.

8. In a bag cleaning machine comprising a holder for releasably engaging the mouth of a bag, a suction means, a cleaning chamber between and connected with the holder and said suction means whereby an air current is drawn through said holder and said chamber to turn the bag simultaneously with its being drawn into said chamber, a conveyor extending into said chamber, valve means for shutting off the air current, means for releasing the bag from the holder, contact means within said chamber adapted to be elevated automatically with the opening of said valve and lowered to contact the bag with the conveyor means at predetermined intervals, additional means for advancing the bag to the exit of the machine, and means for subjecting each bag to a series of cleaning operations during its travel through said machine.

9. In a bag cleaning machine comprising a holder for releasably engaging the mouth of a bag, a suction means, a cleaning chamber between and connected with the holder and said suction means whereby an air current is drawn through said holder and said chamber to draw said bag into said chamber, a rotatable conveyor extending into said chamber, valve means for shutting off the air current, means for releasing the bag from the holder, means for pressing said bag into contact with the conveyor immediately following its release from the holder, said valve means, means for releasing the bag from the holder and means for contacting the bag with the conveyor being, respectively, operable at predetermined time intervals, means for receiving the bag from said conveyor and for conveying the bag to the delivery point of the machine, and a series of cleaning means for operating on the bag during its travel through said machine.

10. In a bag cleaning machine comprising a holder for releasably engaging the mouth of a bag, a suction means, a cleaning chamber between and connected with the holder and said suction means whereby an air current is drawn through said holder and said chamber to draw the bag into said chamber, a rotatable conveyor extending into said chamber, valve means for shutting off the air current, means

for releasing the bag from the holder, a plurality of contact fingers for pressing said bag into contact with the conveyor immediately following its release from the holder, said valve means, means for releasing the bag from the holder and contact fingers being prede-
 terminately operable to open and closed posi-
 tions respectively, additional means for ad-
 vancing the bag to the exit of the machine,
 and a series of cleaning means for operating
 on the bag during its travel through said
 machine.

11. In a bag cleaning machine comprising
 a holder for releasably engaging the mouth
 of a bag, a suction means, a cleaning chamber
 between and connected with the holder and
 said suction means whereby an air current is
 drawn through said holder and said chamber
 to turn the bag simultaneously with its being
 drawn into said chamber, a conveyor extend-
 ing into said chamber, means for shutting off
 the air current, means for releasing the bag
 from the holder, means for pressing said bag
 into contact with the conveyor immediately
 following its release from the holder, and
 means coacting with said conveyor means for
 delivering the bag out of said chamber, means
 for receiving the bag from said conveyor and
 for conveying it to the delivery point of the
 machine, and a series of cleaning means for
 operating on the bag during its travel through
 the machine.

12. In a bag cleaning machine comprising
 an expansible holder for releasably engaging
 the mouth of a bag, a suction means, a clean-
 ing chamber between and connected with the
 holder and said suction means whereby an
 air current is drawn through said holder and
 said chamber to turn the bag simultaneously
 with its being drawn into said chamber, a
 conveyor extending into said chamber, means
 for shutting off the air current, means for re-
 leasing the bag from the holder, means for
 conveying the bags through said chamber,
 and means associated with said chamber and
 coacting with said conveyor for effecting de-
 livery of the bag from said chamber, and
 additional means for receiving the bag from
 said conveyor and for conveying it to the
 delivery point of the machine, and a series
 of cleaning means for operating on the bag
 during its travel through the machine.

13. In a bag cleaning machine comprising
 a holder for releasably engaging the mouth
 of a bag, a suction means, a cleaning cham-
 ber between and connected with the holder and
 said suction means whereby an air cur-
 rent is drawn through said holder and said
 chamber to turn the bag simultaneously with
 its being drawn into said chamber, a rotat-
 able drum extending into said chamber,
 means for shutting off the air current, means
 for releasing the bag from the holder, a plu-
 rality of contact fingers for contacting the bag
 with said drum to effect its delivery beyond

said chamber, means for receiving the bag
 subsequent to its removal from the drum and
 for conveying it to the delivery point of the
 machine, and a series of cleaning means for
 operating on the bag during its travel through
 said machine.

14. In a bag cleaning machine comprising
 a holder for releasably engaging the mouth of
 a bag, a suction means, a cleaning chamber
 between and connected with the holder and
 said suction means whereby an air current is
 drawn through said holder and said chamber
 to draw the bag into said chamber, a convey-
 or extending into said chamber, means for
 shutting off the air current, means for releas-
 ing the bag from the holder, means for con-
 veying the bag through and away from said
 chamber, a brake, a mechanism for actuating
 the brake, and a cam device coacting with the
 mechanism to retard the travel of the bag
 subsequent to its delivery from said cleaning
 chamber, means for conveying the bag to the
 delivery point of the machine, and a series of
 cleaning means for operating on the bag
 during its travel through the machine.

15. In a bag cleaning machine comprising
 a holder for releasably engaging the mouth
 of a bag, a suction means, a cleaning chamber
 between and connected with the holder and
 said suction means whereby an air cur-
 rent is drawn through said holder and said
 chamber to draw the bag into said chamber,
 a conveyor extending into said chamber,
 means for shutting off the air current, means
 for releasing the bag from the holder, means
 for conveying the bag through and away
 from said chamber, a cleaning unit having
 guide means associated therewith, a brake co-
 acting with said guide means, and means for
 actuating said brake to retard the travel of
 the bag over said guide means as it is delivered
 to said cleaning unit, and means for convey-
 ing the bag to the delivery point of the ma-
 chine.

16. In a bag cleaning machine comprising a
 holder for releasably engaging the mouth of
 a bag, a suction means, a cleaning chamber
 between and connected with the holder and
 said suction means whereby an air current is
 drawn through said holder and said chamber
 to draw the bag into the chamber, a conveyor
 extending into said chamber, means for shut-
 ting off the air current, means for releasing
 the bag from the holder, means for guiding
 the bag through and away from said chamber,
 a cleaning unit comprising a rotatable brush,
 tooth means coacting with said brush to ef-
 fect travel of the bag thereover, guide means
 to effect delivery of the bag to said brush,
 a brake, a mechanism for actuating the brake,
 and a cam device coacting with the brake
 mechanism to retard travel of the bag over
 said guide, and means for conveying the bag
 to the delivery point of the machine.

17. In a bag cleaning machine comprising

a holder for releasably engaging the mouth of a bag, a suction means, a cleaning chamber between and connected with the holder and said suction means whereby an air current is drawn through said holder and said chamber to draw the bag into the chamber, a conveyor extending into said chamber, means for shutting off the air current, means for releasing the bag from the holder, means for guiding the bag through and away from said chamber, a cleaning unit for operating on the bag during its travel through said machine, said unit comprising a housing having an opening, a rotatable brush within the housing and operating through said opening, toothed means coating with the brush for advancing the bag thereover, said means being yieldable to compensate for different thicknesses of material passing between said brush and said toothed means, and a suction means connected with said housing whereby a current of air is drawn through said bag as it passes over said opening, and means for conveying the bag to the delivery point of the machine.

18. In a bag cleaning machine comprising a holder for releasably engaging the mouth of a bag, a suction means, a cleaning chamber between and connected with the holder and said suction means whereby an air current is drawn through said holder and said chamber to turn the bag simultaneously with its being drawn into said chamber, a conveyor extending into said chamber, means for shutting off the air current, means for releasing the bag from the holder, means for pressing said bag into contact with the conveyor immediately following its release from the holder, means for receiving the bag from said conveyor and for conveying the bag to the delivery point of the machine, including a series of cleaning units for operating on the bag during its travel through said machine, each of said units comprising a housing having an opening, a rotatable brush within the housing and operating through said opening, toothed means for advancing the bag over said brush, said means being yieldable to compensate for different thicknesses of material passing between said brush and said toothed means, and a suction means connected with said housing of each unit whereby a current of air is drawn through said bag as it passes over said opening.

19. In a bag cleaning machine comprising a holder for releasably engaging the mouth of a bag, a suction means, a cleaning chamber between and connected with the holder and said suction means whereby an air current is drawn through said holder and said chamber to draw the bag into the chamber, a conveyor extending into said chamber, means for shutting off the air current, means for releasing the bag from the holder, means

for conveying the bag through and away from said chamber, means for receiving the bag from said conveyor and for conveying it to the delivery point of the machine, including a series of cleaning units for operating on the bag during its travel through said machine, a guide means associated with each unit, a brake, a mechanism for actuating the brake, and a cam device coating with the mechanism to retard the travel of the bag over each of said guides.

20. In a bag cleaning machine comprising a holder for releasably engaging the mouth of a bag, a suction means, a cleaning chamber between and connected with the holder and said suction means whereby an air current is drawn through said holder and said chamber to turn the bag simultaneously with its being drawn into said chamber, a conveyor extending into said chamber, means for shutting off the air current, means for releasing the bag from the holder, means for contacting said bag with the conveyor immediately following its release from the holder, means for receiving the bag from said conveyor and for conveying it to the delivery point of the machine, including a series of cleaning units for successively operating on alternate sides of the bag during its travel through said machine, each of said units comprising a rotatable brush mechanism, a yielding rotatable toothed mechanism, a guide means, a brake means, and means for operating the brake to retard the travel of the bag over each of said guides.

21. In a bag cleaning machine comprising a holder for releasably engaging the mouth of a bag, a suction means, a cleaning chamber between and connected with the holder and said suction means whereby an air current is drawn through said holder and said chamber to turn the bag simultaneously with its being drawn into said chamber, a conveyor extending into said chamber, means for shutting off the air current, means for releasing the bag from the holder, means for contacting said bag with the conveyor immediately following its release from the holder, means for conveying the bag to the delivery point of the machine, including a series of cleaning units for successively operating on alternate sides of the bag during its travel through said machine, each of said units comprising a rotatable brush mechanism, a yieldable rotatable toothed mechanism, a guide means, a brake means, and means for operating the brake to retard the travel of the bag over said guides, said valve means, means for releasing the bag from the holder, means for contacting the bag with the conveyor and each of the respective brakes being respectively operable at predetermined time intervals.

JOHN W. KITTREDGE. 120
